ABSTRACT: A wedge block combination apparatus for a die casting machine mounted adjacent the rear of the main ram of the said machine and on opposite sides of said ram, the said apparatus having a pair of main wedges and a pair of facing plate wedges. Each of said main wedges having a rabbet recess along its face and end adjacent the main ram of said machine and having one of said facing plate wedges adjustably mounted therein to frictionally engage the rear surface of said main ram of said machine for lockup and quick release of said apparatus.

WEDGE BLOCK FOR DIE CASTING MACHINE

BACKGROUND OF THE INVENTION

1. Field of the Invention

This invention relates to the art of diecasting of metals suitable for such use such as aluminum, brass and magnesium and more particularly to the field of diecasting machines having apparatus for holding the dies in proper alinement during the casting operation.

2. Description of the Prior Art

The prior art apparatus used in the diecasting field to provide proper alinement and lockup during the casting operation of which applicant is familiar is best shown in the U.S. Pat. No. 2,618,823 where a pair of unitary wedge blocks are used to engage the main ram of a diecasting machine. The disadvantages in its use over the wedge block combination apparatus of the present invention include the additional force required in releasing the built up pressure loaded upon the wedge block during the diecasting operation and the slowness of the release resulting therefrom and the lack of adjustability of the ram-engaging surface of the wedge.

SUMMARY

In contrast with the prior art in the diecasting wedge block field, the present invention avoids the disadvantages found in such art in the following respects, among others: The wedge block combination of the present invention provides the advantage of a quick release of the great pressure loaded upon the wedge block during the diecasting operation through the frictional disengagement of the adjustable wedge parts from the main ram of the machine at the conclusion of the diecasting operation. Another advantage is its greater reliability in the alinement of main ram and the die parts. It also reduces the amount of flash extruded from the dies during the operation of the machine. Another advantage is that it eliminates the die end whip or backlash of the die parts during the operation of the machine.

Other advantages more or less ancillary to the foregoing will appear in the following description and the accompanying drawing of the invention.

THE DRAWING

The invention is illustrated in the drawings in which conventional parts are omitted or merely indicated to clarify the specification.

In the drawings:

FIG. 1 is a top plan view of the essential parts of the machine showing the novel wedge block assembly;

FIG. 2 is a fragmentary, somewhat enlarged, sectional plan view of the novel wedge block and activating cylinders shown in FIG. 1;

FIG. 3 is a fragmentary, perspective view of the wedge blocks shown in FIG. 2;

FIG. 4 is a fragmentary and enlarged plan view of the wedge block, partly in section, showing the wedge with the wedge face plate retracted;

FIG. 5 is an elevational view of the wedge block shown in FIG. 4; and

FIG. 6 is a fragmentary and enlarged plan view of the wedge block shown in FIG. 4 with the wedge face plate extended.

THE PREFERRED EMBODIMENTS

The wedge block combination of the invention and the diecasting machine parts associated therewith is illustrated in FIGS. 1 and 2 of the drawing. The base (not shown) of the diecasting machine and the upright frame members (partially shown) for such machine mounted upon said base and upon which the wedge block combination is mounted may be of any suitable structure such as shown in the John A. Perkon, U.S. Pat. No. 2,618,823.

It will be seen that the wedge block combination of the invention and the associated diecasting machine parts comprise a housing member A, a main ram member B and a wedge member C.

5 The said housing member A includes three spaced upright machine frame members designated 10, 11 and 12 and four horizontal rods designated 13, 14, 15 and 16 positioned at the four corners of a theoretic transverse square rigidly connecting the said three upright frame members 10, 11 and 12. The said rods are threaded into the respective frame members with tubular spacers 17 between frame members 10 and 11, said rods are tightly connected to said frame members by any suitable means such as jamb nuts 18.

15 The said main ram member B includes a sleeve 30 slidably mounted in a cylindrical opening 31 of the frame member 11 for longitudinal movement therein, a head 32 on said sleeve 30 adjacent said cylindrical opening 31 that is held thereon by any suitable means such as screws 33. The said sleeve 30 is restricted against rotative movement by suitable means such as a longitudinally extending spline 34 that occupies a keyway 35 in the frame member 11. The said sleeve 30 is internally threaded to receive an externally threaded screw 36. A movable crosshead 37 is slidably mounted on the four horizontal rods 13, 14, 15 and 16 and which provides a movable abutment for the movable die (not shown), the fastening for the movable die is indicated by the T-slots 38 on the face of the crosshead adjacent frame member 12 which has similar T-slots 39 for holding the fixed die (not shown).

25 30 The said screw 36 has a rigidly attached head 40 which is mounted in a circular recess in the crosshead 37 for rotative movement therein. The said screw 36 may be rotated by any suitable means attached to the said head 40 for movement of the crosshead 37 and the movable die toward or away from member 12 and the fixed die positioned thereon, such as is shown in said Perkon U.S. Pat. No. 2,618,823.

35 Referring again to FIGS. 1 and 2 of the drawing it will be seen that the sleeve 30 is mounted adjacent its head 32 in a cylindrical opening 31 of the upright frame member 11 and is held nonrotatably but slidably in said frame member 11 by a spline 34 that occupies a keyway 35. The said head 32 of the sleeve 30 has a connecting rod 41 mounted thereon in axial alinement therewith. The said connecting rod 41 extends outwardly therefrom through an opening 42 in a block 43 of frame member 10 to a plunger 44 positioned in a cylinder 45 affixed to said frame members 10. The said cylinder 45 may receive fluid under pressure and thus through the plunger and connecting rod force the sleeve 30, the screw 36, the crosshead 37 and movable die into coaction with the fixed die.

45 50 The said connecting rod 41 may be made adjustable as to its length as desired by any suitable means such as adjusting nuts 46 thereon adjacent the head 32.

The said wedge member C includes a pair of main wedges 50 and a pair of facing plate wedges 51. As shown in FIG. 3 of the drawing the main wedges 50 are in horizontal and vertical alinement one with the other and are positioned with one face 52 thereof adjacent the periphery of the said head 32 of the sleeve 30 for simultaneous slidable movement forward upon the surface of the head 32 and a similar retractable movement therefrom.

The said main wedges 50 preferably have concave face to face ends 53 that form an arc of a circle substantially the same as the said periphery of the said head 32 of the sleeve 30.

55 60 65 Each of said ends 53 of the main wedges 50 preferably has a rabbet recess at 54 adjacent the said head 32 and along face 52 to receive one of the pair of facing plate wedges 51 having a length, width and thickness substantially equal to the dimensions of the rabbet recesses 54 and having a concave edge 55 to conform to the concave end 53 of said main wedges 50.

70 75 As shown in FIG. 4 preferably the faces 56 of the said rabbet recesses 54 are inclined at an angle of 6° from the plane of the said faces 52 of said main wedges 50 and have the end surfaces 57 of said rabbet recesses 54 at a right angle to said faces 56 thereof. The said facing plate wedges 51 have their faces 58

adjacent said head 32 inclined at an angle of 4° from the plane of the said faces 52 of the main wedges.

As shown in FIG. 6 the said rabbet recesses 54 of the main wedges 50 each have a vertical rectangular integral rib 59 centrally on the surface 56 thereof adjacent said head 32, and the facing plate wedges 51 have on the surfaces 60 thereof adjacent surfaces 56 of the main wedges a vertical rectangular slot 61 centrally thereof to receive one of said ribs 59. Each of said slots 61 preferably should be at least twice the width of said ribs 59 and should be positioned so that when the facing plate wedges 51 are seated in the said recesses 54 of the concave surfaces 53 and 55 of the main wedges and facing plate wedges respectively are in alignment. The width of said slots 61 in excess of the thickness of said ribs 59 determines the range of lateral movement of the main wedges 50 without movement of the facing plate wedges 51 in the quick release operation of the machine.

The main wedges 50 are mounted for operation between members 10 and 11 and are positioned for forward and retractable lateral movement through connections at their rear surfaces 62 to plungers 63 and 64 in cylinders 65 and 66 respectively which are adapted to receive fluid under pressure.

As shown in FIGS. 4, 5 and 6 it will be seen that the said rear surfaces 62 of the main wedges 50 preferably have horizontal cylindrical apertures 67 therein that extend through the main wedges 50 to the end surfaces 57 of said recesses 54. The said apertures 67 have shoulders 68 therein adjacent said end surfaces 57. Good results are obtained by providing one of said apertures 67 at the approximate midpoint of the main wedges 50 between the top edge thereof and the axis of the plunger 41 and another at the midpoint between the bottom edge thereof and said plunger 41.

The facing plate wedges 51 have blind threaded cylindrical apertures 69 in the rear surfaces 70 of the facing plate wedges 51 in axial alignment with said apertures 67 to receive bolts 71 positioned in said apertures 67 for mounting said facing plate wedges 51 in said recesses 54 of the main wedges 50.

The said bolts 71 have flanges 72 adjacent their heads 73 and threads complimentary to the threaded apertures 69 of the facing plate wedges 51 adjacent their other ends. Spiral springs 74 are provided into which said bolts 71 are inserted prior to being placed in said apertures 67. The said springs 74 have one end thereof abutting the flanges 72 of each bolt and the other end abutting said shoulders 68 of the apertures 67 so that when said bolts 71 are threaded into the apertures 69 of the facing plate wedges 51 the said springs 74 will slidably force the facing plate wedges 51 against back surfaces 57 of said recesses 54 to a closed or retracted position with the main wedges 50.

In a modified form the said facing plate wedges 51 may be attached to the said main wedges 50 by making the main wedges 50 without the said rabbet recesses 54 but with the inclined 6 degree surface 56. The portions of the main wedges 50 adjacent the rear ends 57 of said recesses 54 being made as separate elements and as part of the facing plate wedges 51. All other elements or parts of the main wedges 50 and the facing plates wedges 51 remain the same and operate the same as in the preferred form. The said modified form of the facing plate wedges 51 may be attached to the main wedges 50 by screws or other suitable means.

In the machine operation of diecasting, the dies are brought into a casting position by first admitting fluid under pressure 65 into the cylinder 45 to move the main ram member B and the movable die toward the fixed die, aligned therewith, and to force the movable die tightly against the fixed die.

Then as the said main ram moves forward and the head 32 of the sleeve 30 approaches the surfaces 58 of the facing plate wedges 51, the fluid under pressure is admitted to the two cylinders 65 and 66, attached to the main wedges 50, to move the main wedges 50 and the facing plate wedges 51 of wedge members C from their retracted positions toward the head 32 and to force the surface 58 of the facing plate wedges 51, 75

which are inclined 4° into abutting engagement with a similarly inclined peripheral area 75 of the head 32 adjacent thereto. The engagement of the facing plate wedges 51 with the head 32 gives a good surface contact and locks the machine on the 4° angle and thus prevents any movement of the movable die from the fixed die. This allows the insertion of the casting material into the dies under heavy pressure without slippage or misalignment of the dies.

When a casting has been made it is of great importance to secure a quick release of the main ram member B and the wedges from the locking area. The high frictional resistance between the facing plate wedges 51 and the head 32 of the main ram member B on the 4° angle is overcome by admitting fluid under pressure in the cylinders 65 and 66 to retract the main wedges 50 which causes them to move back along the 6° angle of the recesses 54 where the frictional resistance is lower due to the 6° angle of the contacting surfaces. The higher frictional resistance between the facing plate wedges 51 and the head 32 prevents the facing plate wedges 51 from moving and overcomes the force of the spiral springs 74. Thus the facing plate wedges 51 remain in place until the ribs 59 engage the side of the slots 61. At that point much of the high frictional resistance along the 4° surfaces has been relieved so that the main wedges 50 and the facing plate wedges 51 can move back or retract together from the rear of the main ram member B in a quick release with a minimum use of power. When the wedges have retracted and cleared the head 32 of the main ram member B it then can be moved back to release the movable die from the completed casting. This is accomplished by admission of fluid in cylinder 45 under pressure to retract the plunger 44. The machine is thus quickly ready for another casting operation.

Although the foregoing description is necessarily of detailed character, in order that the invention may be completely set forth, it is to be understood that the specific terminology is not intended to be restrictive or confining, and that various arrangements of parts and modifications of detail may be resorted to without departing from the scope or spirit of the invention as herein claimed.

I claim:

1. A wedge block assembly for a diecasting molding machine as described for locking and releasing the main ram unit thereof, the said wedge block assembly comprising:
  - a. a pair of main wedges mounted in said machine transversely of the main ram of said unit and spaced apart on opposite sides thereof adjacent the rear head of said main ram and in alignment therewith;
  - b. means for slidably moving said main wedges in unison forward through the adjacent peripheral area of said rear head and for retracting said main wedges therefrom;
  - c. a pair of facing plate wedges mounted on said main wedges along its side surface adjacent said rear head of said main ram for slidable movement therewith, one of said pair being mounted on a main wedge complementary thereto along its forward side surface for frictional engagement with the peripheral area of said main ram rear head;
  - d. said main wedges, each having the forward portion of its said side surface inclined adjacent the facing plate wedge mounted thereon, and said facing plate wedges, each having its outer surface inclined adjacent the said peripheral area of said main ram rear head, the said inclined surfaces of the said main wedges being greater in degrees of incline from the plane of said side surfaces thereof than the degrees of incline of said facing plate wedges from the plane of said side surfaces of said main wedges;
  - e. means for limited retractive movement of said main wedges independently of said facing plate wedges;
  - f. means for limited slideable retractive movement of said facing plate wedges independently of said main wedges; and
  - g. said peripheral area of said main ram rear head having the surface thereof inclined substantially similar to the said

inclined surfaces of said facing plate wedges for frictional engagement therewith during the locking operation of the said machine.

2. The wedge block assembly as defined in claim 1 in which the means for slidably moving said main wedges are cylinders mounted on said machine adjacent the rear of said wedges having fluid activated plungers therein that are connected to the rear of said wedges.

3. The wedge block assembly as defined in claim 1 in which the means for limited retractive movement of said main wedges independently of said facing plate wedges are ribs on the inclined surfaces of said main wedges with each main wedge having at least one rib and slots on the adjacent surfaces of the facing plate wedges to receive said ribs, the said ribs and said slots extending across the central portion of the respective surfaces of said wedges transversely to the movement of said wedges, the said slots being approximately twice the width of the adjacent ribs and having their forward sidewalls in alinement with the forward sidewalls of said adjacent ribs in their respective retracted positions.

4. The wedge block assembly as defined in claim 1 in which the said inclined surfaces of the main wedges are inclined approximately 6° and the said inclined surfaces of the facing plate wedges and the inclined surface of the peripheral area of

the ram rear head are inclined approximately 4°, respectively, from the plane of the said side surface of the main wedges.

5. The wedge block assembly as defined in claim 1 in which the said main wedges have rabbet recesses along the said inclined surfaces thereof to receive and mount said facing plate wedges therein.

6. The wedge block assembly as defined in claim 5 in which the means for limited slidable movement of said facing plate wedges are spiral springs in apertures of said main wedges having bolts inserted therein for slidably mounting said facing plate wedges to said main wedges.

7. The wedge block assembly as defined in claim 1 in which each of said facing plate wedges has a rear support portion adjacent the said side surfaces of each main wedge, the said rear support portion having spaced longitudinal apertures therein to receive bolts inserted in spiral springs, the said bolts are threaded into alined apertures in the rear of said facing plate under spring tension to permit slidable movement of said facing plate wedge, the said rear portion has spaced transverse apertures therein to receive bolts to be threaded into alined apertures in the said side surface of said main wedge for mounting said spacing plate wedge on said main wedge.
